UNITED STATES PATENT OFFICE

HENRY S. KERBY, OF ALBANY, GEORGIA

DOOR

Application filed February 17, 1930. Serial No. 429,155.

This invention relates to doors, one of the objects being to provide a door especially adapted for use in banks, post offices, and other places where valuables are handled and where it is advantageous to use a door which, when closed and locked, will prevent ingress or egress of undesirable persons.

Another object is to provide a door of this type having means whereby it can be utilized as a screen door during warm weather, said door being readily converted to a solid panel door or a glass panel door by the substitution of sections provided for that purpose.

A further object is to provide a door which can be mounted to swing in the usual manner or, if desired, can be employed as a unit of a revolving door.

With the foregoing and other objects in view, which will appear as the description proceeds, the invention resides in the combination and arrangement of parts and in the details of construction hereinafter described and claimed, it being understood that changes in the precise embodiment of the invention herein disclosed may be made within the scope of what is claimed without departing from the spirit of the invention.

In the accompanying drawings the preferred form of the invention has been shown.

30 In said drawings,

Figure 1 is a front elevation of the door having assembled therewith panels whereby drafts and moisture can be excluded.

Figure 2 is a section on line 2—2, Figure 1.

Figure 3 is an enlarged section on line 3—3, Figure 1.

Figure 4 is an elevation of the outer side of the door, the screen panels being broken away.

Figure 5 is a section on line 5—5, Figure 1.

Figure 6 is a section on a reduced scale similar to Figure 3 showing the door provided with a sealing flap such as used on the unit of revolving doors.

Referring to the figures by characters of reference, 1 and 2 designate opposed frames each formed of an angle strip, the said strips being oppositely disposed and constituting

the top, bottom, and sides of the door. The strips are formed with inwardly extending flanges 3 and seated between these flanges are the edge portions of a metal grille or lattice 4 held to the strips 1 and 2 by welding. This grille or lattice extends throughout the width and height of the door and is of sufficient strength to frustrate attempts to break through the door.

At intermediate points the sides of strip 1 are connected by superposed oppositely arranged angle strips 5 welded or otherwise suitably connected to the strip 1 and spaced apart to receive between them a filling strip 6 of wood or other suitable material. Similarly oppositely disposed angle strips 7 are welded or otherwise connected to intermediate portions of the sides of strip 2 and are likewise spaced apart to receive between them a filling strip 8 of wood or the like. These strips 5 and 7 cooperate with the strips 1 and 2 to form inner and outer, upper and lower panel receiving recesses 9, 10, 11, and 12. Each of the outer recesses 11 and 12 is adapted to receive a screen 13 the frame 14 of which fits snugly in the recess.

A screen 15 has its frame 16 seated snugly in the lower recess 12. The inner recesses 9 and 10 can be used for holding panels adapted to be employed during cold weather. For example the lower recess 10 can be provided with a removable solid panel 17 fitting snugly therein while the other recess 9 can be provided with a removable window 18 the frame 19 of which fits snugly in the recess. Bolts 20 are extended through the corner portions of the frames 14, 16, 17, and 19, and also through the flanges of the strips making up the frame of the door. Each bolt has both of its ends screw threaded as shown particularly at 21 in Figure 3 and these ends are adapted to be engaged by cap nuts 22 which serve to bind against the outer surfaces of the adjacent frames, thereby to hold all of the frames firmly but detachably within the respective recesses. Obviously any one of the frames can be removed readily whenever desired but at all times the grille or lattice 4 will remain in place at the center of the door.

where it will serve as an efficient protecting means.

The door herein described can be mounted on hinges in the usual way or, if desired, 5 can be one of the units of a revolving door. In the latter event the door may be provided, on its outer free edge or edges with a flexible strip 23 adapted to make a wiping contact with the adjacent surfaces of the door and 10 closure, thereby to form a weather tight connection between the door and adjacent parts.

The filling strips 6 and 8 are employed for receiving door handles and other attachments to be connected to the door.

15 What is claimed is:

1. A door including a frame formed of spaced angle strips constituting the top, bottom and sides of the door, a grille having its edge portions extending between and connected to said strips, angle strips connecting the sides of the frame to provide upper and lower, inner and outer recesses, and door panels removably mounted in the recesses.

25 2. A door including angle strips oppositely disposed and constituting the top, bottom and sides of the door, said strips being spaced apart, a metal grille having its edge portions secured between the strips and extending 30 throughout the length and width of the door, said strips defining inner and outer recesses, and a panel removably mounted in each recess.

35 3. A door including angle strips oppositely disposed and constituting the top, bottom, and sides of the door, said strips being spaced apart, a metal grille having its edge portions secured between the strips and extending throughout the length and width of the door, 40 said strips defining inner and outer recesses, a panel removably mounted in each recess, and means extending through the panels and strips for binding them together detachably.

4. A door including opposed metal angle 45 strips spaced apart and forming the top, bottom and sides of the door, a grille having its edge portions seated between and secured to the angle strips, angle cross strips connecting the sides of the door and disposed in pairs, 50 the cross strips of each pair being spaced one above the other, filling strips interposed between said spaced strips, there being recesses formed between the said cross strips and the top, sides and bottom of the door, 55 panels removably mounted within said recesses, and means extending through the panels and strips for detachably fastening the panels in the recesses.

In testimony that I claim the foregoing as 60 my own, I have hereto affixed my signature.

HENRY S. KERBY.
